ABSTRACT OF THE DISCLOSURE

This application describes a bleach-fix bath for use in processing colour photographic material comprising a mild oxidising agent, a silver-halide solvent and a bleach-fix accelerator which is a water soluble selenium compound selected from defined classes of selenosemi-carbazides and analogous bis-compounds, 1,2,4-triazole-3-selenols and 5,5-bis, 1,2,4-triazole-3-selenols, the invention including the baths per se and their use in colour processing of photographic material.

This invention relates to the processing of photographic material comprising silver halide emulsion layers to yield material having colour dye images therein.

In the processing of conventional colour photographic material a developable silver salt image is developed with an aromatic primary amino developing agent of the para-phenylene diamine type (a so-called "colour developer") in the presence of a compound (a so-called "colour coupler") which will combine with the oxidation products of the colour developer to form an azomethine or quinone-imine dye. The dye is thus formed in situ with the developed silver image. Subsequently the product must be treated with a bleach bath and a fixing bath or a combined bleach-fix bath thereby to remove silver and any residual silver halide or other silver salt, leaving in the product only the dye image.

In the silver-dye-bleach process of colour photography the photographic material comprises at least one silver halide emulsion layer which includes as a dispersion therein an organic dyestuff of the type which can be destroyed (or bleached) by finely divided silver in a suitable treatment bath. The organic dyestuff is usually an azo dye. Most commonly three such silver halide emulsion layers are present each of which is sensitive to a different region of the visible spectrum and each of which contains a different azo dye. The usual processing sequence for the production of a dye image in the material is after an imagewise exposure to develop the material in a black and white developer. The development is then stopped and the unexposed silver halide is fixed out. Then after washing the material is treated in a dye-bleach bath which oxidises the silver image and simultaneously reduces (bleaches) the dye in the region of the silver image. The silver salts and any residual silver must then be removed. This is usually accomplished by washing the material after its treatment in the dye-bleach bath and then treating it in a bleach bath followed by a fixing bath or treating it in a combined bleach-fix bath. The photographic material then contains a dye image only; this dye image being usually a direct positive reproduction of the original.

In one commercially available silver-dye-bleach material the amount of residual silver left after the dye-bleach step is not negligible because this material requires to be processed so that the dye-bleach step is terminated before all the image silver has been used in reducing the dye. Thus in the processing of this silver-dye-bleach material

in particular it is essential that an effective silver bleach step succeeds the dye-bleach step in order to ensure that the residual silver is removed as completely as possible from the material.

5 In both the processing of conventional colour photographic material and in the processing of silver-dye-bleach material the use of a combined bleach-fix bath is preferable because it results in a reduction of the processing time and of the cost of processing equipment required. 10 Normally a bleach-fix bath comprises a mild oxidising agent for example a ferric chelate complex, a cupric complex, a salt or a cobalt (III) complex together with a silver halide solvent or fixing agent for example a water-soluble thiosulphate or a water-soluble thiocyanate. Strong oxidising agents cannot be used because they tend to oxidise the silver halide solvent.

15 Stable bleach-fix solutions comprising ferric chelate complexes and sodium thiosulphate may be obtained but because of the weak oxidising power of the ferric chelate complex such bleach-fix bath can only be used commercially for the processing of photographic materials with a fairly low silver content.

20 According to the present invention in the processing of photographic material comprising silver halide emulsion layers to yield material having colour dye images therein there is provided a bleach-fix step which comprises treating the photographic material with a stable bleach-fix bath which comprises an aqueous solution of a mild oxidising agent and a silver halide solvent which is either a 25 water-soluble thiosulphate or a water-soluble thiocyanate in the presence of a bleach-fix accelerator which is selected from (a) a water-soluble selenosemi-carbazide of the general Formula I:

30 wherein one of R_1 and R_2 is a hydrogen atom or an alkyl, aralkyl or aryl group or a group $\text{R}_6\text{CO}-$ where R_6 is a hydrogen atom or an alkyl, alkoxy or heterocyclic group, or a group $\text{NR}_7\text{R}_8-\text{CSe}-$ where R_7 and R_8 are each hydrogen atoms or alkyl groups and the other of R_1 and R_2 is a hydrogen atom or an alkyl group, R_3 is a hydrogen atom or an alkyl, aralkyl or aryl group, one of R_4 and R_5 is a hydrogen atom or an alkyl, aralkyl or aryl group and the other of R_4 and R_5 is a hydrogen atom or an alkyl group but at least one of R_3 , R_4 or R_5 being a hydrogen atom and there being not more than one group selected from aryl, aralkyl and heterocyclic present in the compound or (b) a water-soluble compound of the general Formula II:

nol wherein the triazole rings are linked directly or via a link

wherein n is 1-4 and wherein one nitrogen atom in each of the triazole rings carries a substituent selected from a hydrogen atom and an alkyl, aryl and aralkyl group.

It is to be understood that the triazole-selenol compounds of (c) and (d) above have been defined with reference to their selenol form but these compounds may be present in their tautomeric selenone form in which case there is an additional substituent hydrogen atom in the ring or rings.

The preferred compounds for use in the present invention are those of Formula I wherein each of R_1 - R_6 are hydrogen atoms or alkyl groups. Other preferred compounds are those of Formula II wherein each of R_9 - R_{16} is a hydrogen atom. The preferred triazole-selenols of (c) are those wherein the 5-carbon atom carries an alkyl or hydroxy group and one of the nitrogen atoms carries a substituent hydrogen atom. The preferred bis-triazole-selenols of (d) are those wherein one nitrogen atom in each of the triazole rings carries a substituent hydrogen atom.

By "stable bleach-fix bath which comprises an aqueous solution of a mild oxidising agent and a silver halide solvent" is meant a bleach-fix bath wherein the oxidising agent is strong enough to bleach the silver but is not strong enough to oxidise the silver halide solvent, i.e. the thiocyanate or the thiosulphate, to an appreciable degree.

The preferred mild oxidising agents for use in the present invention are ferric chelate complexes or diaquo-tetramminecobalt (III) complexes.

By ferric chelate complex is meant a co-ordination compound of the ferric ion and a compound which comprises nitrogen and/or oxygen-containing co-ordinating groups. The most important co-ordinating groups are amino, heterocyclic nitrogen, carboxyl and carbonyl groups.

The preferred ferric chelate complex for use in the bleach-fix step of the present invention is a ferric ethylenediamine-tetraacetic acid complex. It is to be understood that this compound may be used as such in the preparation of a bleach-fix bath or it may be formed in situ in a bleach-fix bath by ethylenediaminetetraacetic acid reacting with a ferric salt e.g. ferric chloride. In the examples which follow the ferric ethylenediaminetetraacetic acid complex has been formed in situ.

Other ferric chelate complexes which may be used in the present invention are for example pyridine-2:6-dicarboxylateferrate (III) complex, iminodiacetatoferate (III) complex and nitrilo-triacetate-ferrate (III) complex.

The selenosemicarbazides of the above Formula I are known compounds as shown by the references set forth below.

The following Formula III indicates the nitrogen atom referred to in the references.

4-phenylselenosemicarbazide—preparation described by Jensen and Frederiksen, Z. anorg. allgem. Chem. 230, 31-3 (1936)

2-phenylselenosemicarbazide—preparation described by Mautner and Kumler, J. Amer. Chem. Soc. 97-101 (1956)

4-ethylselenosemicarbazide—preparation described by Huls and Renson, Bull. soc. chim. Belges 65, 684-95 (1956)

4-propylselenosemicarbazide—preparation described by M. Colland-Charon, Huls and Renson, Bull. soc. chim. Belges 71, 541-53 (1962)

preparations described by Colland-Charon, Huls and Renson, Bull. soc. chim., Belges 71, 554-62 (1962):

1-phenylselenosemicarbazide, and
1-(p-tolyl) selenosemicarbazide

preparations described by Jensen, Felbert, Pedersen and Svaholm, Acta chem. Scand. 20 (1) 278-81 (1966):

10 preparations described by Bulka, Ahlens and Tucek, Chem. Ber. 100 (4) 1373-8 (1967):
2-methyl-4-phenylselenosemicarbazide
4-(p-chlorophenyl)selenosemicarbazide and
4-(p-methoxyphenyl)selenosemicarbazide

15 20 15 However compounds of Formula I wherein R_1 is a group $R_5 \text{CO}-$, i.e. the monocyl derivatives of the selenosemicarbazides may be prepared by reacting an equimolecular amount of a selenosemicarbazide with an acylating agent, for example an acid chloride or an acid anhydride; the reaction usually being carried out in an organic solvent at a low temperature.

The compounds of Formula I wherein one of R_1 and R_2 is a group $\text{NR}_7\text{R}_8-\text{CSe}-$ where R and R_8 are each hydrogen atoms or alkyl groups may be prepared by reacting a compound of the general Formula IV:

30 where R_4 and R_5 have the meanings assigned to them in Formula I, with hydrogen selenide.

The compounds of Formula II may be prepared by reacting a selenosemicarbazide with a dibasic acid chloride; the reaction usually being carried out in an organic solvent at a low temperature.

35 40 The production of the 1,2,4-triazole-3-selenols of (c) wherein there is attached to the 5-carbon atom an alkyl, group comprises reacting a selenosemicarbazide of the general Formula V:

45 wherein each of R_{24} , R_{25} , and R_{26} is a hydrogen atom or two of them are hydrogen atoms and one of them is a group selected from alkyl, aryl and aralkyl, with an acid chloride of the general formula R_{21}COCl in the presence of a base or with an acid anhydride of the general formula

50 $\text{R}_{21}\text{COOR}_{21}$ wherein R_{21} is an alkyl group and then ring closing this acyl derivative by heating it in the presence of an alkali metal salt of a weak acid for example an acetate or carbonate, or in the presence of an alkali metal hydroxide or an alkoxide.

55 The production of the 1,2,4-triazole-3-selenols of (c) wherein there is attached to the 5-carbon atom a hydrogen atom or an alkyl group which comprises from 1 to 4 carbon atoms comprises reacting a selenosemicarbazide of the above general Formula V with a carboxylic acid of

60 the general formula R_{27}COOH where R_{27} is a hydrogen atom or an alkyl group having 1 to 4 carbon atoms, to form the acyl derivative of the selenosemicarbazide, and then ring closing this acyl derivative by heating it in the presence of an alkali metal salt of a weak acid, for example an acetate or carbonate, or in the presence of an alkali metal hydroxide or an alkoxide.

The production of the 1,2,4-triazole-3-selenols of (c) wherein there is attached to the 5-carbon atom an hydroxy group comprises reacting a selenosemicarbazide of the above Formula V with an alkoxy-, aryloxy- or aralkyloxy-haloformate in the presence of a base to form the alkoxy-, aryloxy- or aralkoxycarbonyl derivative of the selenosemicarbazide and ring closing this compound in the presence of an alkali metal salt of a weak acid or

75 in the presence of an alkali metal hydroxide or alkoxide,

with the elimination of the appropriate alcohol or phenol.

The production of the 1,2,4-triazole-3-selenols of (c) wherein there is attached to the 5-carbon atom an amino, alkylamino, arylamino or aralkylamino group comprises reacting a selenosemicarbazide of the general Formula VI:

wherein R_{37} is a hydrogen atom or an alkyl, aryl or aralkyl group and each of R_{38} , R_{39} , and R_{40} is a hydrogen atom or two of them are hydrogen atoms and the third is a group selected from alkyl, aryl and aralkyl, with an alkali metal hydroxide to effect ring closure and separating the desired product.

Selenosemicarbazides of general Formula VI may be prepared by reacting a bis-selenourea with a one molecular proportion of a methylating agent in a basic medium.

The production of the bis-1,2,4-triazole-selenols may be effected by reacting a selenosemicarbazide with a dibasic acid chloride in the presence of a base to form the acyl derivative and then ring closing the acyl derivative by heating it in a basic medium e.g. in the presence of an alkali metal carbonate, hydroxide or ethoxide.

The bleach-fix accelerators of use in the present invention are preferably added to the bleach-fix bath but they may be present during the bleach-fixing treatment adsorbed to or absorbed in the colour photographic material. In the processing of conventional colour photographic material, i.e. colour negative or colour reversal material bleach-fix accelerators of use in the present invention may be present in any treatment bath or wash bath which is used in the colour development process between the development step and the bleach-fix step. Exemplary of such baths are stop baths and stop-fix baths. The bleach-fix accelerators should not be present, however, in the developing solution as they interfere with the development of the colour material. For the same reason the bleach-fix accelerators of use in the present invention should not be present initially in the photographic material.

In the processing of silver-dye-bleach material the bleach-fix accelerators may be present in the wash bath which succeeds the dye-bleach treatment bath and precedes the bleach-fix bath but the bleach-fix accelerators should not be present during the dye-bleach treatment as they can interfere with this treatment step. Thus the bleach-fix accelerators should not be present initially in the silver-dye-bleach photographic material.

According to another embodiment of the present invention there is provided a stable-bleach-fix bath which comprises an aqueous solution of a mild oxidising agent, as hereinbefore defined, a silver halide solvent which is either a water-soluble thiosulphate or a water-soluble thiocyanate and a bleach-fix accelerator which is either a selenosemicarbazide of the above Formula I or a compound of the above Formula II, or a 1,2,4-triazole-3-selenol of the type (c) as hereinbefore defined, or a bis-1,2,4-triazole-3-selenol of the type (d) as hereinbefore defined.

Preferably in this aspect of the invention the mild oxidising agent is a ferric chelate complex or a diaqua-tetrammine-cobalt (III) complex.

It is preferred that the concentration of the bleach-fix accelerators of the type (a), (b), (c) or (d) as hereinbefore defined present in the bleach-fix bath is greater than 1 mg. per litre of bleach-fix bath. The most preferred

amount being 100 mg. of bleach-fix accelerator per litre of bleach-fix bath.

It is preferred that the concentration of the bleach-fix accelerators of the type (a), (b), (c) or (d) as hereinbefore defined present in a stop bath or a stop-fix bath or in a wash bath is greater than 1 mg. per litre of the solution.

The following examples will serve to illustrate the invention.

In the examples which follow the following bleach-fix accelerators were used:

- (1) 3-selenosemicarbazide
- (2) 1-formyl-3-selenosemicarbazide
- (3) 1-acetyl-3-selenosemicarbazide
- (4) 1-propionyl-3-selenosemicarbazide
- (5) 2-methyl-3-selenosemicarbazide
- (6) 4-methyl-3-selenosemicarbazide
- (7) 1,1'-dimethyl-3-selenosemicarbazide
- (8) 1,2-dimethyl-3-selenosemicarbazide
- (9) 1,2,4-trimethyl-3-selenosemicarbazide
- (10) 1,1',4-trimethyl-3-selenosemicarbazide
- (11) 1-acetyl-4-methyl-3-selenosemicarbazide
- (12) 1-acetyl-4-benzyl-3-selenosemicarbazide
- (13) 4-benzyl-3-selenosemicarbazide
- (14) 1-phenyl-3-selenosemicarbazide
- (15) 2-phenyl-3-selenosemicarbazide
- (16) 4-phenyl-3-selenosemicarbazide
- (17) 2-methyl-4-phenyl-3-selenosemicarbazide
- (18) 1-(2-furoyl)-3-selenosemicarbazide
- (19) 1,1'-oxalyl-bis (3-selenosemicarbazide)
- (20) 1,2,4-triazole-3-selenol
- (21) 5-methyl-1,2,4-triazole-3-selenol
- (22) 4,5-dimethyl-1,2,4-triazole-3-selenol
- (23) 5,5'-bis (1,2,4-triazole-3-selenol)
- (24) 5,5'-methylene-bis(1,2,4-triazole-3-selenol)
- (25) 5,5'-ethylene-bis (1,2,4-triazole-3-selenol)
- (26) 1-ethoxycarbonyl-3-selenosemicarbazide

In the examples which follow a colour negative film was used which was made up as follows:

Layer order and sensitivity:	Silver coating weight in mg. of Ag/decimetre ²
Nonstress	13.4
Blue sensitive	13.4
Colloidal silver filler layer	13.1
Green sensitive topcoat	13.1
Intralayer	16.0
Green sensitive subcoat	16.0
Interlayer	17.5
Red sensitive topcoat	13.6
Red sensitive subcoat	13.6
Base of cellulose triacetate	73.6
Total	73.6

In this film:

the blue sensitive layer contained yellow colour coupler of the formula:

the green sensitive layers each contained a magenta colour coupler of the formula:

the red sensitive layers each contained a cyan colour coupler of the formula:

The following processing solutions were used in Examples 1-4

STOP-FIX

Sodium thiosulphate pentahydrate	g	171
Sodium acetate anhydrous	g	31.4
Sodium sulphite anhydrous	g	4.3
Acetic acid glacial	ml	35
Potassium alum	g	17.0
Ammonium chloride	g	43
Water to 1 litre.		

BLEACH-FIX

Disodium tetraborate decahydrate	g	12.5
Boric acid	g	22.5
Sodium hydroxide	g	10.0
Ethylenediamine tetraacetic acid	g	16.2
Disodium salt of ethylenediamine tetraacetic acid	g	3.5
Ferric chloride (60% w/v. solution)	ml	15.0
Sodium thiosulphate pentahydrate	g	95
Sodium sulphite anhydrous	g	4.0
Water to 1 litre.		35

CONDITIONER

Disodium salt of ethylene diamine tetraacetic acid	g	0.50
Sodium carbonate anhydrous	g	4.5
Formaldehyde (40% w/v. solution)	ml	10
Lissapol N (8% w/v. solution)	ml	1.7
Water to 1 litre.		

All processing solutions and wash water were used at 75° F.

The constitution of the colour developing solutions used in the following examples was as follows:

COLOUR DEVELOPER A

G.		
Sodium metaborate	53.3	
Sodium hydroxide	2.0	
Sodium sulphite anhydrous	3.9	55
Potassium bromide	0.70	
Hydroxylamine sulphate	2.34	
Sodium sulphate anhydrous	7.8	
4-amino-N-ethyl-N-(β -hydroxyethyl)-aniline sulphate	6.0	60
Water to 1 litre.		

COLOUR DEVELOPER B

G.		
Sodium metaborate	80	
Sodium sulphite anhydrous	2.0	
Potassium bromide	1.0	
Hydroxylamine sulphate	2.6	
4-amino-N-ethyl-N-(β -hydroxyethyl)-aniline sulphate	4.6	
Water to 1 litre.		

EXAMPLES

Pieces of the colour negative film were fogged and processed in a number of processing sequences all containing the use of a bleach-fix bath. The metallic silver remaining

75

in the film at the end of each processing sequence was measured by analysis and expressed in mg. of Ag/decimetre².

When the bleach-fix bath or stop-fix bath contained one of the specified bleach-fix accelerators a reduction in the amount of residual silver resulted. In the examples the residual silver resulting when one of the accelerators was used is expressed as a percentage of that obtained when no accelerator was used (referred to as the control).

10

Example 1

Pieces of the colour negative film were processed as follows:

		Minutes
15	Colour developer B	10
Stop-fix		14
Wash		4
Bleach-fix		6
Wash		4
Conditioner		4
Wash		4
Dry.		

¹ With and without accelerator.

The silver content of the pieces of film was analysed with the following results:

TABLE 1

Accelerator compound No.	Concentration of accelerator in the stop-fix bath, mg./dm. ³	Residual silver mg./dm. ²	Percent of control
1 No accelerator	300	1.0	8.4
100	11.96		100

Example 2

Pieces of the colour negative film were processed as follows:

		Minutes
Colour developer B		10
Stop-fix		14
Wash		4
Bleach-fix		6
45 Conditioner		4
Wash		4
Dry.		

¹ With and without accelerator.

The silver content of the pieces of film was analysed with the following results:

TABLE 2

Accelerator compound No.	Concentration of accelerator in stop-fix bath, mg./dm. ³	Residual silver as percent of control
1	300	10.9
21	300	17.4

Example 3

Pieces of the colour negative film were processed as follows:

		Minutes
65 Colour developer A		6
Stop-fix		4
Wash		4
70 Wash		4
Bleach-fix		16
Conditioner		4
Wash		4
Dry.		

¹ With and without accelerator.

The silver content of the pieces of film was analysed with the following results:

TABLE 3

Accelerator compound No.	Concentration of accelerator in bleach-fix bath, mg./litre	Residual silver as percent of control
1	100	5.6
2	150	6.6
3	100	10.6
26	150	35
4	150	25
20	150	26
21	100	9.3

Example 5

A positive tripack colour material intended for the silver dye-bleach system comprising silver halide emulsions containing bleachable azo-dyes "Cibachrome" manufactured by Ciba-Geigy A.G. of Switzerland was given a neutral wedge exposure and processed, the processing sequence being as follows:

Development: 10 minutes

p-Methyl-aminophenol-sulphate	g--	1
Sodium sulphite anhydrous	g--	20
Hydroquinone	g--	4
Sodium carbonate anhydrous	g--	10
Potassium bromide	g--	2
Water to 1 litre.		

Stop-fix: 4 minutes

Sodium thiosulphate pentahydrate	g--	200
Sodium sulphite anhydrous	g--	20
Water to 1 litre.		

Wash: 8 minutes

Dye-bleach: 20 minutes

Sulphuric acid, 96%	ml--	27.5
Potassium iodide	g--	10
Solution of 0.9 g. 2,3-dimethyl-6-aminquinoxaline in 50 ml. ethanol	ml--	15
Water to 1 litre.		

Wash: 4 minutes

Bleach-fix: 6 minutes

Disodium tetraborate decahydrate	g--	12.5
Boric acid	g--	22.5
Sodium hydroxide	g--	10.0
Ethylenediaminetetraacetic acid	g--	16.2
Disodium salt of ethylenediaminetetraacetic acid dihydrate	g--	3.5
Ferric chloride (60% w./v. solin.)	ml--	15
Sodium thiosulphate pentahydrate	g--	95.0
Sodium sulphite anhydrous	g--	4.0
Selenosemicarbazide	mg--	100
Water to 1 litre.		

15 Wash: 8 minutes

Dry

The processed material was satisfactory and substantially no residual silver was left in the material even in the areas of high exposure. Similar silver-dye-bleach material was exposed and processed using the same solutions as set forth above except that the bleach-fix solution contained no selenosemicarbazide. Even when the material had been treated in the bleach-fix bath for 25 minutes it was unsatisfactory because it had a high minimal density due to 25 the incomplete removal of the residual silver in the areas of high exposure.

What we claim is:

1. In the processing of photographic material comprising exposed and developed silver halide emulsion 30 layers to yield material having colour dye images therein the step of treating the exposed and developed photographic material with a stable bleach-fix bath which comprises an aqueous solution of a mild oxidising agent which is strong enough to bleach the silver but not strong enough to oxidise silver halide solvents and a silver halide solvent which is either a water-soluble thiosulphate or a water-soluble thiocyanate in the presence of a bleach-fix 35 accelerator which is selected from (a) a water-soluble selenosemicarbazide of the general formula:

40 wherein one of R_1 and R_2 is a hydrogen atom or an alkyl, aralkyl or aryl group or a group R_6CO- where R_6 is a hydrogen atom or an alkyl, alkoxy or heterocyclic group, or a group NR_7R_8-CSe- where R_7 and R_8 are each hydrogen atoms or alkyl groups and the other of R_1 and

45 R_2 is a hydrogen atom or an alkyl group, R_3 is a hydrogen atom or an alkyl, aralkyl or aryl group, one of R_4 and R_5 is a hydrogen atom or an alkyl, aralkyl or aryl group and the other of R_4 and R_5 is a hydrogen atom or an alkyl group, at least one of R_3 , R_4 or R_5 being a hydrogen atom and there being not more than one group selected from aryl, aralkyl and heterocyclic present in the compound or (b) a water-soluble compound of the general formula:

50 wherein each of R_9 – R_{16} is a hydrogen atom or an alkyl group there being not more than four alkyl substituent groups in the compound and at least one of R_9 , R_{10} , R_{11} , R_{14} , R_{15} , and R_{16} being a hydrogen atom and X is a 55 $-(CH_2)_m-$

55 linkage group wherein m is 0 to 4, or (c) a water-soluble 1,2,4-triazole-3-solenol wherein the 5-carbon atom carries a substituent selected from a hydrogen atom or an alkyl, hydroxy, amino, alkylamino, arylamino or aralkylamino group and one of the nitrogen atoms carries a substituent selected from a hydrogen atom or an alkyl, aralkyl 60 or aryl group, or (d) a water-soluble 5,5-bis-1,2,4-tri-

azole-3-selenol wherein the triazole rings are linked directly or via a link

—(CH₂)_n—

wherein *n* is 1-4 and wherein one nitrogen atom in each of the triazole rings carries a substituent selected from a hydrogen atom and an alkyl, aryl and aralkyl group.

12. In the processing of exposed and developed photographic material comprising silver halide emulsion layers to yield material having colour dye images therein, the step of treating the exposed and developed photographic material with a stable bleach-fix bath which comprises an aqueous solution of a mild oxidising agent which is strong enough to bleach the silver but not strong enough to oxidise silver halide solvents and a silver halide solvent which is either a water-soluble thiosulphate or a water-soluble thiocyanate in the presence of a bleach-fix accelerator which is selected from the group consisting of

3-selenosemicarbazide;
1-formyl-3-selenosemicarbazide;
1-acetyl-3-selenosemicarbazide;
1-propionyl-3-selenosemicarbazide;
2-methyl-3-selenosemicarbazide;
4-methyl-3-selenosemicarbazide;
1,1'-dimethyl-3-selenosemicarbazide;
1,2-dimethyl-3-selenosemicarbazide;
1,2,4-trimethyl-3-selenosemicarbazide;
1,1',4-trimethyl-3-selenosemicarbazide;
1-acetyl-4-methyl-3-selenosemicarbazide;
1-acetyl-4-benzyl-3-selenosemicarbazide;
4-benzyl-3-selenosemicarbazide;
1-phenyl-3-selenosemicarbazide;
2-phenyl-3-selenosemicarbazide;
4-phenyl-3-selenosemicarbazide;
2-methyl-4-phenyl-3-selenosemicarbazide;
1-(2-furoyl)-3-selenosemicarbazide;
1,1'-oxalyl-bis (3-selenosemicarbazide);
1,2,4-triazole-3-selenol;
5-methyl-1,2,4-triazole-3-selenol;
4,5-dimethyl-1,2,4-triazole-3-selenol;
5,5'-bis(1,2,4-triazole-3-selenol);
5,5'-methylene-bis(1,2,4-triazole-3-selenol);
5,5'-ethylene-bis(1,2,4-triazole-3-selenol) and
1-ethoxycarbonyl-3-selenosemicarbazide.

13. A process for the production of photographic material having colour dye images therein from exposed and developed photographic material comprising silver halide emulsion layers and including the step of treating the exposed and developed photographic material with a stable bleach-fix bath in the presence of a bleach-fix accelerator selected from the group consisting of

3-selenosemicarbazide;
1-formyl-3-selenosemicarbazide;
1-acetyl-3-selenosemicarbazide;
1-propionyl-3-selenosemicarbazide;
2-methyl-3-selenosemicarbazide;
4-methyl-3-selenosemicarbazide;
1,1'-dimethyl-3-selenosemicarbazide;
1,2-dimethyl-3-selenosemicarbazide;
1,2,4-trimethyl-3-selenosemicarbazide;
1,1',4-trimethyl-3-selenosemicarbazide;
1-acetyl-4-methyl-3-selenosemicarbazide;
1-acetyl-4-benzyl-3-selenosemicarbazide;

- 14
- 4-benzyl-3-selenosemicarbazide;
1-phenyl-3-selenosemicarbazide;
2-phenyl-3-selenosemicarbazide;
4-phenyl-3-selenosemicarbazide;
5 2-methyl-4-phenyl-3-selenosemicarbazide;
1-(2-furoyl)-3-selenosemicarbazide;
1,1'-oxalyl-bis(3-selenosemicarbazide);
1,2,4-triazole-3-selenol;
5-methyl-1,2,4-triazole-3-selenol;
10 4,5-dimethyl-1,2,4-triazole-3-selenol;
5,5'-bis(1,2,4-triazole-3-selenol);
5,5'-methylene-bis(1,2,4-triazole-3-selenol);
5,5'-ethylene-bis(1,2,4-triazole-3-selenol) and
1-ethoxycarbonyl-3-selenosemicarbazide.
- 15 14. A stable bleach-fix bath which comprises an aqueous solution of a mild oxidising agent which is strong enough to bleach the silver but not strong enough to oxidise silver halide solvents, a silver halide solvent which is either a water-soluble thiosulphate or a water-soluble thiocyanate and a bleach-fix accelerator which is selected from the group consisting of
- 20 3-selenosemicarbazide;
1-formyl-3-selenosemicarbazide;
1-acetyl-3-selenosemicarbazide;
1-propionyl-3-selenosemicarbazide;
2-methyl-3-selenosemicarbazide;
4-methyl-3-selenosemicarbazide;
1,1'-dimethyl-3-selenosemicarbazide;
30 1,2-dimethyl-3-selenosemicarbazide;
1,2,4-trimethyl-3-selenosemicarbazide;
1,1',4-trimethyl-3-selenosemicarbazide;
1-acetyl-4-methyl-3-selenosemicarbazide;
1-acetyl-4-benzyl-3-selenosemicarbazide;
40 4-benzyl-3-selenosemicarbazide;
1-phenyl-3-selenosemicarbazide;
2-phenyl-3-selenosemicarbazide;
4-phenyl-3-selenosemicarbazide;
2-methyl-4-phenyl-3-selenosemicarbazide;
40 1-(2-furoyl)-3-selenosemicarbazide;
1,1'-oxalyl-bis(3-selenosemicarbazide);
1,2,4-triazole-3-selenol;
5-methyl-1,2,4-triazole-3-selenol;
4,5-dimethyl-1,2,4-triazole-3-selenol;
45 5,5'-bis(1,2,4-triazole-3-selenol);
5,5'-methylene-bis(1,2,4-triazole-3-selenol);
5,5'-ethylene-bis(1,2,4-triazole-3-selenol) and
1-ethoxycarbonyl-3-selenosemicarbazide.
